TOY CUPBOARD OR SIMILAR ARTICLE

Kay Stanley, Chicago, Ill.

Application August 1, 1955, Serial No. 37,251

Term of patent 7 years

(Cl. D34—15)

Figure 1 is a perspective view of a toy cupboard or similar article showing my new design; and

I claim:

The ornamental design for a toy cupboard or similar article, substantially as shown.
